US0D1054490S

(12) **United States Design Patent** (10) Patent No.: **US D1,054,490 S**
(45) Date of Patent: ** Dec. 17, 2024

(54) **MULTIFUNCTION PRINTER**

(71) Applicant: **Zhuhai Pantum Electronics Co., Ltd.**,
Guangdong (CN)

(72) Inventors: **Aiguo Yin**, Guangdong (CN); **Jibing Peng**, Guangdong (CN); **Geng Wang**, Guangdong (CN); **Ke Mou**, Guangdong (CN); **Weisheng He**, Guangdong (CN); **Huizhao Deng**, Guangdong (CN); **Tian Wang**, Guangdong (CN); **Rubo Li**, Guangdong (CN); **Yanhua Li**, Guangdong (CN)

(73) Assignee: **Zhuhai Pantum Electronics Co., Ltd.**,
Zhuhai (CN)

(**) Term: **15 Years**

(21) Appl. No.: **35/517,531**

(22) Filed: **Apr. 27, 2023**

(80) **Hague Agreement Data**

Int. Filing Date: **Apr. 27, 2023**

Int. Reg. No.: **DM/229432**

Int. Reg. Date: **Apr. 27, 2023**

Int. Reg. Pub. Date: **Jun. 16, 2023**

(30) **Foreign Application Priority Data**

Oct. 27, 2022 (CN) 2022307109640
